CLAIM

The ornamental design for a bottle with cap, as shown and described.

DESCRIPTION

FIG. 1 is a top perspective view of a bottle with cap;
 FIG. 2 is a bottom perspective view of a bottle with cap;
 FIG. 3 is a front view of the bottle with cap;
 FIG. 4 is a rear view of the bottle with cap;
 FIG. 5 is a left side view of the bottle with cap;
 FIG. 6 is a right side view of the bottle with cap;
 FIG. 7 is a top view of the bottle with cap; and,
 FIG. 8 is a bottom view of the bottle with cap.

The broken lines represent portions of the bottle with cap that form no part of the claimed design.
